UNITED STATES PATENT OFFICE.

GUSTAVE A. SAMUELS, OF BELLINGHAM, WASHINGTON.

COMBINED BEDSTEAD AND TABLE.

1,039,817.

Specification of Letters Patent.

Patented Oct. 1, 1912.

Application filed January 20, 1912. Serial No. 672,400.

To all whom it may concern:

Be it known that I, GUSTAVE A. SAMUELS, a citizen of the United States, residing at Bellingham, in the county of Whatcom and 5 State of Washington, have invented certain new and useful Improvements in Combined Bedsteads and Tables, of which the following is a specification.

This invention relates to improvements in 10 combined bedsteads and tables, and has for one of its objects to provide a simply constructed device whereby a bedstead may be quickly and readily transformed into a table without material alteration of the construction of the bedstead.

Another object of the invention is to provide a device of this character which may be readily applied without material structural change to bedsteads of various forms 20 and sizes and which does not interfere with the employment of the device as a table.

Another object of the invention is to provide a device of this character which may be readily dismembered for shipment or 25 storage.

With these and other objects in view, the invention consists in certain novel features of construction as hereafter shown and described, and then specifically pointed out in 30 the claims, and in the drawings illustrative of the preferred embodiment of the invention: Figure 1 is a side elevation of the improved device arranged as a bed; Fig. 2 is a transverse section on the line 2—2 of Fig. 1; Fig. 3 is a side view of the improved device arranged as a table; Fig. 4 is a transverse section on the line 4—4 of Fig. 3; Fig. 5 is an enlarged perspective view of one of the supporting brackets; Fig. 6 is a 35 detail view illustrating a modification in the construction.

Corresponding and like parts are referred to in the following description and indicated in all the views of the drawings by the 45 same reference characters.

The bed portion of the improved device is formed substantially in the usual manner and comprises a "head" 10, a "foot" 11 and sides 12—13, these parts being of the usual 50 construction except that the head and foot members are of the same height. The sides 12—13 are detachably coupled to the head and foot members by the usual hook devices indicated at 14—15. The bed portion will 55 be provided with the usual mattress and springs, but as these portions form no part

of the present invention, they are not illustrated. The sides 12—13 are formed with their upper edges extending horizontally from end to end, while the head and foot members correspond substantially in height to the framework of an ordinary table, and thus project a considerable distance above the upper edges of the sides 12—13. Hinged at 16—17 to the upper edges of the sides 60 12—13 are side members 18—19 which when elevated fill the gap between the upper edges of the sides 12—13 and the head and foot members as shown in Figs. 3 and 4. By this means the mattress and springs and bed 65 clothing of the improved device are entirely concealed when the device is employed as a table as hereafter more fully explained. When employed as a bed, the filler members 18—19 are folded down parallel to the sides 70 75 12—13 as shown in Figs. 1 and 2.

The attachments for supporting the table portion of the improved device are connected to the head and foot near their ends, four of the devices being employed, and are precisely alike, and the description of one will suffice for all. Attached to each of the head and foot members near their ends, is a supporting bracket comprising a base plate 20 having vertical guides 21 spaced apart and 80 open at the top and closed at the bottom, as shown. Detachably supported between the guides 21 and resting at its lower end upon the closed bottom of the guides, is a standard 22 having a vertical slot 23. The standard 85 90 is thus readily detachable from the bracket, as will be obvious.

Pivoted at 24 in the upper end of the bracket is an L-shaped member comprising two arms 25—26. Pivoted at one end at 27 upon 95 opposite sides of the elbow of the L-shaped member, are bars 28—29, the opposite end of the bars being coupled by a pin 30 extending through the slot 23 of the standard. The pin 30 bears upon the bottom of the 100 slot 23 when the L-shaped member is in its outward position as shown in Fig. 1, and thus supports the L-shaped member and its attachments in open position, as hereafter explained.

The supporting devices are arranged in pairs, one pair being attached to the head 10, and another pair attached to the foot 11 of the bedstead, and attached to each pair of the members 26 is an outer table section 110 31, and hinged at 32 to each outer table section 31, is an inner table section 33. Each

table section corresponds in width to one-fourth of the total length of the bedstead so that when the L-shaped members 25-26 are moved upwardly and inwardly the fronting edges of the inner table section 33 will abut centrally of the bedstead as shown in Fig. 3, and rest centrally upon the upper edges of the sides 18-19 whereby the table sections are supported from deflection. 5

10 When the table sections are disposed in open position to enable the device to be employed as a bed as shown in Fig. 1, the inner or free edges of the inner table sections 33 will rest upon the upper ends of the head and 15 foot sections 10-11, and are secured in this position by bolts 34. The bolts are also employed to assist in supporting the table sections in open position, as represented in Fig. 1. Similar bolts 35 are attached to the extension members 18-19 and operate to hold the members 18-19 in elevated position as shown in Fig. 3, and may also be utilized to hold the members 18-19 in their lowered position, as shown in Fig. 1. 20

25 It will be noted that the outer edges of the table sections 31 extend for some distance beyond the elbow portions of the L-shaped supporting members so that when the device is arranged as a table as shown in Fig. 3, 30 the ends of the table overhang the supports and thus conceal them from observation, so that the device presents the same appearance as an ordinary table.

35 The supporting members between the bedstead structure and the table sections are of metal as light as possible consistent with the strains to which they will be subjected and

may be japanned, plated, painted or otherwise protected or ornamented.

Having thus described the invention, what is claimed as new is:

1. The combination with a bedstead including head and foot members, of table sections each formed of coacting members hingedly united, and means for hingedly uniting the outer member of each section respectively to the head and foot members, the coacting members being so proportioned that the inner member of each section will bear upon the head and foot boards and stand in vertical alinement therewith when in open position. 45

2. The combination with a bedstead including head and foot members and side rails, supplemental side members hingedly united to the side rails and adapted to swing into vertical alinement with the same, table sections each formed of coacting members hingedly united, and means for hingedly uniting the outer member of each section respectively to the head and foot members, whereby the inner member of each table section may be supported respectively upon the head and foot member and extend in vertical alinement therewith when in open position and bear upon the upper edges of the supplemental side members when in closed position. 55

In testimony whereof, I affix my signature in presence of two witnesses.

GUSTAVE A. SAMUELS. [L.S.]
